IGNITION COIL SYSTEM

Ferdon D. Bentley, Detroit, Mich., assignor, by
mesne assignments, to Radio Corporation of
America, New York, N. Y., a corporation of
Delaware

Application August 28, 1934, Serial No. 741,763

12 Claims. (Cl. 175—361)

This invention relates to ignition coils for gasoline motors and the like, and has particular reference to a device for the elimination of static interference when radio apparatus is employed in the immediate vicinity of an internal combustion engine.

Various devices have been resorted to in the past for suppression of the interference above referred to. Among these are the so-called "supressors" which are applied to the spark plugs. Various forms of electrostatic shielding have also been provided for isolating a radio receiver from static effects of an ignition system. Since the radio apparatus is usually operated from the same battery as that which serves the ignition system, shielding does not provide the complete isolation of the radio receiver which is desired. I have discovered, however, that the structure of the ignition coil may be so designed as to very considerably reduce the interference both as transmitted through space between the ignition system and the radio receiver, and also as transmitted through the conductors to the common battery.

It is an object of my invention to provide an ignition system the electrical characteristics of which are such as to substantially eliminate sparking interference with the ordinary operation of a radio receiver.

Other objects of my invention are: to provide an ignition coil structure suitable for use in an ignition system whose battery is common to that of a radio receiver; to provide adequate shielding in an ignition coil such that static interference, as above referred to, is substantially suppressed; and to provide means for substantially eliminating a so-called "corona-effect" which, if it takes place between the primary and secondary windings of an ignition coil, is a contributing cause of static interference.

The foregoing and other objects of my invention will be apparent upon reading a complete description thereof, details of which are given in the ensuing part of the specification wherein reference is made to the accompanying drawing in which

Figure 1 is a cross-sectional view showing a preferred embodiment of an ignition coil according to my invention; and

Fig. 2 is a wiring diagram showing an ignition coil of my invention in its association with other elements of an ignition system for a gasoline motor.

My preferred ignition coil structure, as shown in Fig. 1 comprises preferably a laminated iron

core 3 about which is wrapped a sheet of insulating material 4. The secondary winding 5 is preferably disposed next to the insulation 4 and internally of primary winding 6. Between the primary and secondary windings, I provide an electrostatic shield 7, faced on both sides thereof by insulating members 8 and 9. The shield 7 may be composed of sheet copper. The usual precautions are taken that the abutting edges of the shield 7 do not make contact with one another, since, if they did, an undesirable short-circuited loop would be provided for induced currents therein.

The arrangement of the coil leads contributes most effectively to the efficiency of operation of my invention. Preferably, the starting lead of the secondary winding is connected to a sheet metal member 10 which is disposed about one end of the laminated core 3. A molded insulation end piece 11 is so constituted as to provide on the inner side a cup into which the laminated core 3 may fit. The sheet metal member 10 intervenes between the laminations of the core and the inner wall of this cup. The molded member 11 is also provided with an outer cup which may, if desired, be lined by a metallic receptacle 12. After the ignition coil unit has been assembled, a nail 13, or the like, may be driven through a central hole in the insulation member 11 thereby electrically interconnecting the cup lining 12, the sheet metal lead 10, which connects with the starting lead of the secondary winding 5 and the laminations of the core 3.

The finish lead of the secondary winding and the start lead of the primary winding are connected by a conductor 14 (common to both) to a terminal post 15 so that connection may be made with the breaker-points 16 (see Fig. 2) of the ignition system.

The outer lead of the primary winding may be connected as by means of a conductor 17 to a terminal post 18 for connection with an ignition switch 19. Another end piece 20 of molded insulation is provided with an internal cup for holding the core in position. The molded end pieces 11 and 20 may, therefore, be seen to be similar in construction except that the member 11 only is provided with a receptacle for an ignition wire to the distributor 29.

The assembly of my ignition coil unit may be completed by encasing the unit within the outer cylindrical member 21, the ends of which may be permanently locked into engagement with metal flanges 22. The latter, if desired, may be molded into the peripheries of the members 11 and 20

respectively. The edges of the members 22 may be spun over the flanged portions of the casing member 21. The entire ignition coil unit may, if desired, be supported by a clamp 23, or in any other desired manner.

In order to prevent induced currents in the members 21 and 22, these parts are split and the intervening space is preferably filled with insulating compound. The clamp 23, if it is in two pieces, may be provided with insulation members 31 about the bolt 32 so as to avoid a short circuit for induced currents.

The electrostatic shield 7 may be electrically connected to the outer shell 21 as by means of a conductor 33. These elements may then be grounded in any suitable manner; for example, through the clamp members 23 which, presumably are supported by a metallic portion of the chassis.

20 It will be noted that the cylindrical walls of the insulation member 8 extend considerably beyond the ends of the coils. The purpose of this arrangement is to avoid a "corona effect" which has been known to take place between the primary and secondary coils. This effect is very objectionable.

30 The very marked improvement in the operating characteristics in my ignition coil unit, as compared with units heretofore known, may be attributed in part to the arrangement of the coil leads 14 adjacent the electrostatic shield 7. These particular coil leads are at the low potential ends of the primary and secondary respectively.

35 Referring to Fig. 2, I show the relation between the connections to my ignition coil unit and the other elements of my ignition system such as contribute further to the improved performance characteristics of the system as a whole. In this 40 diagram will be seen the common battery 24 grounded at one end and having a lead at the other end to the ignition switch 18. The ignition switch is preferably shunted by a capacitor 25 having a value of the order of say .5 mf. The 45 ignition switch 18, as before stated, connects with the terminal post 18 of the ignition coil unit. A conductor 26 is shown interconnecting the breaker points 16 with one lead each of the primary and secondary windings, the leads being 50 connected to the terminal post 15 (Fig. 1). The breaker points may, if desired, be shunted by a capacitor 27 having preferably a value of about .25 mf.

55 A conductor 28 interconnects the terminal 18 with the distributor 29. In series with the conductor 28 I may insert a resistor 30, the value of which may be of the order of 10,000 ohms.

60 The operation of the system as shown in the diagram of Fig. 2 is such as to need no further explanation to those skilled in the art.

I claim as my invention:

1. An ignition circuit transformer comprising a core member, primary and secondary windings, an electrostatic shield separating the primary from the secondary, insulating means disposed internally and externally of said shield, a terminal post common to the outer lead of the inner winding and to the inner lead of the outer winding, a grounded metallic outer casing, and 65 means including an electrical connection between said shield and said casing for substantially suppressing the effects of ignition-circuit interference upon a nearby radio apparatus.

2. An ignition circuit transformer comprising 70 a core, an insulating member surrounding said

core, a secondary winding about said insulating member, an inner and an outer insulating sleeve surrounding said secondary winding, a grounded electrostatic shield disposed between said inner and outer sleeves, a primary winding exterior to 5 said outer sleeve, a grounded metallic casing for said transformer, a binding post for the outer lead of said primary winding, a distributor lead receptacle connected both to said core and to the inner lead of said secondary winding, and means including a conductor common to the inner lead of said primary winding and the outer lead of said secondary winding for substantially preventing the radiation of ignition-circuit interference to a zone occupied by radio apparatus. 15

3. An ignition circuit transformer comprising shieldingly encased primary and secondary coils, a grounded electrostatic shield of thin metal interposed between said primary and said secondary, a breaker-point connection to the outer 20 terminal of said secondary and the inner terminal of said primary, an ignition switch connection to the outer terminal of said primary, a laminated iron core, and means including a distributor connection to the inner terminal of said 25 secondary and to said core for substantially suppressing the effects of ignition-circuit interference upon a nearby radio apparatus.

4. An ignition circuit transformer in accordance with claim 3 and having means including 30 laminations of insulating material between which said electrostatic shield is disposed, at least one of said laminations extending substantially beyond the lengthwise limits of the coil convolutions. 35

5. In a transformer, a secondary coil, a primary coil wound over said secondary, ignition-interference shielding means insulatingly interposed between said primary and said secondary, a conductor interconnecting the "finish"-lead 40 of said secondary and the "start"-lead of said primary, separate conductors to the "start"-lead of said secondary and to the "finish"-lead of said primary, respectively, an outer metallic casing and a grounded connection both to said casing 45 and to said shielding means.

6. In a device for suppressing the interference effect upon radio apparatus caused by an ignition system, an ignition transformer having primary and secondary coils, a split tubular casting therefor of magnetic material which is grounded, a grounded electrostatic shield separating said primary from said secondary, and means including a tubular member of insulating material over-reaching the coil ends and the 55 shield ends sufficiently to substantially eliminate corona leakage between said coils and from either of said coils to said shield.

7. An ignition-circuit transformer for internal combustion engines comprising in combination a 60 core member, primary and secondary windings, an electrostatic shield separating said primary from said secondary, a container for said windings having a split cylindrical wall of magnetic material and end pieces of non-metallic material, 65 and means including a grounded conductor connecting with said shield and with the cylindrical wall of said container for substantially suppressing the effects of ignition-circuit interference upon a nearby radio apparatus. 70

8. A transformer for use with a common battery system for a radio apparatus and for the ignition circuit of an internal combustion engine, comprising primary and secondary windings, a core member electrically connected to the 75

5 "start"-lead of the inner one of the two said windings, a metallic ignition-interference shield separating said windings, a metallic container surrounding said windings, a ground terminal for said shield and said container, and a breaker-point common to the "finish"-lead of the inner winding and to the "start"-lead of the outer winding.

9. The invention as set forth in claim 8 where-
10 in means including an insulation member are provided adjacent said ignition - interference shield for substantially suppressing a corona discharge between said windings and from either of said windings to said shield.

15 10. In a transformer, primary and secondary coils wound one over the other, ignition-interference shielding means insulatingly interposed between said coils, a laminated core and a cylindrical container both of magnetic material,
20 means including a conductor common to said shielding means and to said cylindrical container for maintaining the same at substantially ground

potential, means for equalizing potentials applied to the "finish"-lead of the inner coil and to the "start"-lead of the outer coil, and means for equalizing potentials applied to the "start"-lead of the inner coil and to the laminated core. 5

11. A device in accordance with claim 10 characterized in that said ignition-interference shielding means and said cylindrical container are so constructed as to offer substantially an infinite impedance to induced currents circulating there- 10 in.

12. In a device for suppressing the interference effect upon radio apparatus caused by the ignition system of an internal combustion engine, a transformer having primary and secondary 15 windings, an electrostatic shield separating said windings, and means including members of insulating material at least one of which over-reaches the edges of said shield sufficiently to substantially eliminate corona leakage between said wind- 20 ings and said shield.

FERDON D. BENTLEY.
